UNITED STATES PATENT OFFICE.

ROY D. TOLMAN, OF WORCESTER, MASSACHUSETTS.

REGISTERING AND INDORSING BALLOT BOX.

Application filed April 14, 1922. Serial No. 552,762.

My invention relates to that class of mechanical ballot boxes which are used at elections under the Australian ballot system where each legal ballot is received, indorsed and registered by mechanical means. The voter of to-day controls the destiny of our nation through his paper ballot and as he deposits his ballot in the ballot box, that ballot should be protected. While numerous attempts have been made to protect the ballot as it leaves the voter's hand, none have succeeded so well as those that use an indorsing ballot box. With the foregoing improvements there has been designed a ballot box which can be used successfully at all elections whether a large bulky or a small ballot is used. The operating movements are positive and so simple that an electric motor could be used to operate the ballot box in place of the usual election official. A paper ballot when once placed in the ballot chute cannot be withdrawn but is fed forward and is indorsed by the endorsing rolls, thus placing an official seal upon each ballot as it is cast. The ballot chute is closed automatically by each ballot as it is being indorsed and it remains closed during the process of indorsing and registering each ballot. When the ballot drops into the bottom of the ballot box, it has been legally cast and a stroke of a bell announces that fact. The ballot chute automatically opens as the ballot drops into the bottom of the ballot box. Numerous improvements have been made to render the operating parts positive in action under all types of ballots as well as making it more durable for use by all kinds of election officials.

Referring to the accompanying drawings, Figure 1 is a top view of the mechanism embodied in my improved ballot box. Figure 2 is a side elevation of the same shown in normal position. Figure 3 is a side elevation, the same as in Figure 2 but shown in operative position with a ballot passing through the indorsing mechanism. Figure 4 is a central sectional view on line 4-4 Figure 1 but with the mechanism in the position as shown in Figure 3. Figure 5 is a detailed view of the feed rolls. Figure 6 is a detached view of the indors-

ing mechanism showing a modified form of construction.

The mechanism as shown in the accompanying drawings represents the mechanical section of the Australian ballot box which apparatus usually sits in the top of the ballot box case and is enclosed throughout with the exception of a hole for the operating crank and an opening for the ballot chute. The supporting framework 10 is secured to the center board 11 of the ballot box and it is through an opening 12 in the center board 11 that the ballot drops into the bottom of the case after having been indorsed and registered. Secured within the sides of the framework 10 is an inclined feed board 13 upon which the ballot is deposited by the voter and pushed forward until the forward end of the ballot comes in contact with the main feed roll 14 and upper feed roll 15.

The main feed roll 14 is turned by the election official through a crank on the outside of the ballot box, not shown, and it is upon this roll 14 while normally an independent loose roll that all operating parts function whenever a ballot is passed through the machine. The main feed roll 14 is mounted upon a shaft 16 held within the framework 10 and the shaft 16 extends outward sufficiently to enable a crank to be applied by the election official.

The shaft is turned in the direction of the arrow 17 and by so doing the ballot which had been placed by the voter in the ballot chute 18 is drawn forward by the two feed rolls 14 and 15. While the average voter places his ballot straight in the chute, many times it has been found that the ballots are placed obliquely to the forward movement of the rolls and in these cases the ballot follows a crooked path and finally stops against the side of the frame. To straighten out the crooked paths that some ballots pursue and to make them all pass through straight and smooth, I have accomplished that object by making the feed roll 15 in severals sections with the two central sections 19 slightly larger in diameter than the two outer sections on each side. By this construction, there are two feed rolls in running contact, one roll of which has more frictional contact in its central section than the outside sections. A turntable is

1,618,691

thus formed to straighten the paths of the ballots should their advancing end strike the side wall of the frame.

The upper feed roll 15 is the tension roll 5 and it is held in place by two side arms 20 pivoted at 21 with proper tension springs 22 applied to the side arms. The two feed rolls 14 and 15 are similarly grooved as shown at 23 to admit a series of rolls which together form the indorsing roll 24. The indorsing roll normally rests in the shallow grooves of the main feed roll 14 and it is through this connection of the rolls that I am always enabled to secure proper adjustment of the entire mechanism. When the ballot is drawn forward between the two feed rolls 14 and 15, the forward end of the ballot comes in contact with the embedded indorsing roll 24 and the ballot 10 raises the roll out of the shallow grooves 23 of the main feed roll 14 and allows the indorsement of the ballot to take place as the ballot passes through the rolls.

The indorsing roll 24 with its shaft 25 turns freely in the swinging frame 26 which is mounted upon studs 27 held in the sides of the framework 10. The indorsing roll 24 is shown with one band of printing type 28 secured to its central section and as the indorsing roll 24 is raised by the passage of a ballot, it comes into running contact with an inking roll 29. The inking roll 29 is held in a swinging frame 30 mounted upon studs in the framework and held under tension of a spring 31. The inking roll 29 is normally held out of engagement with the indorsing roll 24 and no distribution of ink takes place unless a ballot is being indorsed. Heretofore the life of an inking roll has been short from the fact that a deep groove is gradually worn in the center of the roll and at that time it loses contact with the indorsing roll and is thrown away. I have made it possible to use one inking roll much longer by having an adjustable mounting for the roll so that it can be set to be engaged by the indorsing roll at different points in its length. The inking roll 29 is mounted upon a hollow sleeve 32 which sleeve is adjustably held by set screws 33 upon the inking roll shaft 34.

After a ballot has been presented to the feed rolls, it has a forward movement and cannot be withdrawn from the fact that there are suspended in the ballot chute 18 two retaining plates 35 which permit only the forward movement of the ballot as shown in Fig. 4.

The registering mechanism is dependent upon the indorsing mechanism and as the indorsing roll operates in running contact with the main feed roll, the connection between the register and main operating shaft is obviously a simple one. The indorsing roll 24 has its shaft 25 extended outwardly

beyond the swinging frame 26 on the front side of the framework in order to attach the registering mechanism thereto. While the registering mechanism is operated through the movement of the shaft 16 of the main feed roll; no action of the register takes place unless a ballot has been presented to the feed rolls 14 and 15.

Attached securely to the shaft 16 adjacent to the frame 10 is a pinion 36 capable of rotating independently as the shaft is turned. Whenever a ballot is being cast, the feed rolls carry the ballot forward to the indorsing roll 24 which is raised by the passage of the ballot and in so doing, the shaft 25 of the indorsing roll with proper intermediate connections raises a rack 37 into engagement with the pinion 36. As the main shaft 16 with the pinion 36 continues to rotate, the engagement of the rack 37 therewith carries the rack forward and with it an extension rod 38 which connects the register 29 to the rack and pinion mechanism. The extension rod 38 is pivoted at 40 to the register and extends substantially horizontally to the rack held beneath the pinion. The rack 37 is secured to the loose end of the extension rod 38 and the rack normally rests upon the hub 41 of a pivoted lever 42 secured at 43 to the framework. The intermediate connections made between the indorsing roll 24 and the rack and pinion mechanism comprise the pivoted lever 42 having its free end connected to an adjustable link 44 and this adjustable link being pivoted at its other end to the shaft of the indorsing roll 24.

Whenever the indorsing roll 24 has been raised by the passage of a ballot, the rack and pinion mechanism become engaged and it is very essential that the rack and pinion move together in a slightly loose engagement. Should the rack and pinion mesh in rigid engagement, the ballots would become torn while passing by the indorsing roll. To insure a proper link connection between the raised indorsing roll and the engaged rack and pinion, I provide the adjustable link 44 so constructed that by turning the right and left handed screw 45, the rack can be raised or lowered from the pinion 36. Ballots of different thicknesses are used at different elections and I have made it possible to adjust the ballot mechanism for thick or thin ballots and this adjustment is held by check-nut 46.

In the operation of the rack and pinion mechanism, the ballot through the indorsing roll 24 raises the pivoted lever 42 and while the rack and its extension rod 38 rests normally upon the hub of the lever 42, the upward movement of the lever 42 causes a projection pin 47 thereon to be raised. The pin 47 on the lever 42 extends across the plane and below the rack 37 and as the pin

moves upward, it raises the rack into engagement with the pinion. As the pinion continues to rotate, the rack moves forward until it drops off upon the end of the projection pin 47 as shown in Fig. 3. The rack remains in this position until the ballot drops off into the ballot receptacle, then it resumes the position as shown in Fig. 2.

In the forward movement of the rack, it 10 is desirable to disengage the rack and pinion at a predetermined point. To accomplish a positive action of disengagement, a cam plate 68 is secured to the extension rod 38 in a position to engage a releasing pin 69 held upon the framework and cause the rack to fall upon the side of the pin as it passes over the pin 47 as shown in Fig. 3.

Whenever the extension rod 38 operating 20 the register arm moves forward to carry over a new figure on the register, a steel spring 48 upon the hub of the register is being flexed. This spring 48 stands in a flexed position as long as the ballot remains in its passage, then as the ballot drops off the rolls, 25 the spring straightens and throws the register arm into its normal position. There is considerable movement to this spring 48 in one action and at an election where thousands of ballots are cast, the strain upon 30 this spring is very great at the center. In order to insure a greater endurance for this spring, it has been found best to form the convolutions 49 extra large at the center. The convolutions are sufficiently large to 35 encircle the hub 50 of the register with so much clearance that when the spring is contracted, no part of its curvature will make contact with the register hub 50. By this formation of the spring, I make it possible 40 to distribute the strain throughout the entire center of the spring.

It is desirable to announce the fact of a ballot being finally cast by the stroke of a bell, so there is mounted upon the extension 45 rod 38 of the register, a lug 51 which is so placed that it will engage the operating end 52 of the bell hammer 53. As the ballot is being cast, the hammer assumes the position as shown in Fig. 3 and when the ballot drops off completely indorsed, the hammer is engaged by the lug 51 which gives the bell one stroke.

In order that absolute accuracy may be obtained in the operation of my ballot box, 55 I desire to make it possible to cast only one ballot at a time. In case there is a line of voters before the ballot box, the voters in their haste to cast their ballots have a tendency to lap their ballots or place them close 60 together before the first ballot has received its complete indorsement, in this case the register would be in question for two ballots might be counted as one. With the present instrument, I have secured means for closing 65 the ballot chute 18 automatically as the bal-

lot enters the machine and keeping the chute closed during the period of indorsement. When the indorsement is complete, the ballot drops off into the bottom of the box and the ballot chute is opened automatically.

In Figs. 1 and 2 the ballot chute is shown open while in Figs. 3 and 4 the chute is shown closed, a sliding cover 55 is mounted upon the top of the framework 10 and is capable of being moved in ways 56 by ballot 70 operating levers hereinafter described. Extending downward on each side of the cover 55 are lugs 57 with coil springs 58 attached thereto having their free ends secured to the sides of the framework. Normally the 80 coil springs 58 hold the sliding cover 55 back so that the ballot chute remains in open position.

Whenever a ballot is presented to the machine, the rack and pinion mechanism become engaged, the register extension rod 38 is carried forward and mounted upon the extension rod 38 is an arm 59 which co-acts with a swinging frame 60 capable of closing the ballot chute 18. The swinging frame 60 90 is pivoted at 61 with its main bearing 62 extending through the machine, the extension arms 63 extend upward and short links 64 join the swinging frame 60 to the lugs 95 57 of the sliding cover 55.

The register extension rod 38 while performing its other functions is capable of operating the sliding cover 55 through the arm 59 engaging the swinging frame 60 and whenever a ballot has caused the ballot chute 100 to be closed, the springs 58 stand expanded until the ballot drops off the indorsing roll and at that time the action of these springs is required to open the sliding cover. There 105 is therefore a positive action used in closing the ballot chute while in reopening the chute, the movement is controlled by springs.

Following the details of protection afforded in the construction of my improved ballot box, it will be seen that I have made it possible to take each ballot separately, indorse and register the instrument completely before a second ballot can enter the ballot chute.

At the close of the polls, the ballot box is closed and the operating crank is removed by reverse movement as it is screwed upon the shaft 16. At times it has been found that the shaft turns backward with the crank and to positively hold it from backward movement, I provide an eccentric block 65 mounted on the side of the framework to co-act with a serrated surface 66 upon the periphery of the main feed roll 14. It is the serrated surface which effects a complete 110 blocking of the shaft and allows the crank 115 to be positively removed.

In providing for a mechanism to work with thin and thick ballots, I am aware that other forms of adjustment may be made 120 without departing from the scope of my 125 130

invention. As a modified form of construction, I have shown the rack and pinion mechanism in Fig. 6 so constructed and connected that while it will take care of thick and thin ballots, no adjustment is required. Many times it is unwise to have an adjusting screw on a machine for it is always turned by the inexperienced man. In this modified form I have shown a flexible spring 67 so tempered that it will yield sufficiently for thick ballots and allow the thin ones to go through with ease. The yielding of the spring allows the machine to operate without tearing the ballots.

15 Having described my invention in full, I desire to claim by Letters Patent:

1. The combination, with a feed board forming a ballot chute leading to a series of rolls, a rack and pinion mechanism mounted in connection with said rolls, and means controlled by the passage of a ballot through the rolls for operating the rack and causing the ballot chute to be closed.

2. The combination of a ballot chute leading to a series of rolls, a rack and pinion mechanism adapted to be moved into engagement by the passage of a ballot and means controlled by the movement of the rack for closing the ballot chute.

30 3. The combination of a ballot chute leading to a series of rolls, a sliding cover for the ballot chute, a rocking frame operating the sliding cover and means controlled by the passage of a ballot for operating the proper leverage to rock the frame and close the ballot chute.

4. The combination of a ballot chute leading to a series of rolls, means controlled by the passage of a ballot through the rolls 40 for operating the register arm and a pro-

jection carried by the register arm adapted to engage a sliding cover and cause the ballot chute to be closed.

5. The combination of a ballot chute leading to a series of rolls, an indorsing roll controlling the movement of a rack and pinion mechanism, a sliding cover attached to a swinging frame and means controlled by the passage of a ballot for causing the rack to engage the swinging frame, move the sliding cover and close the ballot chute.

6. A balloting machine having a ballot chute with a sliding cover, a swinging frame attached to the sliding cover, an indorsing roll controlling the movement of the sliding cover and means whereby the sliding cover will be opened upon the passage of a ballot.

7. A balloting machine having a ballot chute with a sliding cover, a swinging frame attached to the sliding cover, an indorsing roll controlling the movement of the sliding cover and means whereby the sliding cover will be closed during the passage of a ballot.

8. A balloting machine having two feed rolls adapted to receive and forward the movement of ballots, one of said rolls having its central section slightly larger in diameter than the outer sections whereby a ballot in its passage is adapted to turn into a straight course should its advancing end 65 engage the side wall of the frame.

9. A balloting mechanism comprising receiving rolls with an indorsing roll rotating therewith, a rack and pinion mechanism adapted to be engaged upon the passage of a ballot and means carried by the rack for disengaging the rack and pinion mechanism at a predetermined point.

ROY D. TOLMAN.
